MODULATION

George L. Usselman, Port Jefferson, N. Y., assignor to Radio Corporation of America, a corporation of Delaware

Application July 20, 1932, Serial No. 623,558
Renewed January 11, 1936

7 Claims. (Cl. 179—171)

This invention relates to signalling means and in particular to means whereby the characteristics of high frequency oscillations, other than the amplitude, are varied in accordance with signals to be transmitted.

It has been found that ordinary amplitude modulated high frequency oscillations in transmission from the sending station to the receiving station are subject to what is known as fading effects. This is a decided disadvantage since it introduces drop-outs and errors in the signal. Even where diversity receivers are used to receive the amplitude modulated signals the effect of fading is a serious disadvantage.

I have found that if the high frequency oscillations are modulated in phase or in frequency in accordance with the signal to be transmitted they are less subject to the effect of fading than amplitude modulated waves. The reason why phase or frequency modulated oscillations in telegraph transmission are subject to a less extent to fading effects than oscillations modulated otherwise is that a greater amount of the transmitter power is available for transmission. In other words a transmitter can operate at full output on phase or frequency modulation, while it is necessary to reduce the power output to about one quarter for amplitude modulation. Assuming equal power output, reduction of fading may be slightly greater in phase or frequency modulation.

Obviously, this method of signalling is of the utmost importance since one of the main drawbacks to signalling is the effect of fading of the transmitted oscillations. Especially is this method desirable now in telegraph transmission since it is adaptable where diversity reception methods are not in use.

In my United States application Serial No. 616,026, filed June 8, 1932, I disclose in detail a method of and means for producing high frequency oscillations and phase or frequency modulating the same in a novel manner with modulating oscillations or voice frequency modulations obtained from a novel thermionic tube arrangement which, by a single switching operation, may be made to operate as a modulating frequency oscillation generator, or as an amplifier for the voice frequencies, with which the high frequency oscillations are to be phase or frequency modulated. The modulating frequency oscillations generated by this novel tube arrangement and the amplified voice frequency potentials, whichever is used for modulating the high frequency oscillations, are passed through a symmetrical

thermionic stage which affects the modulation in

phase or frequency of the high frequency oscillations generated.

The present invention relates to an improvement in modulators of the type disclosed in the above referred to application.

It has been found through practice that when an ordinary phase modulator, or a phase modulator as disclosed in said application, is used on the high frequencies there is usually an unbalance in the excitation voltage delivered by the phase shifting circuit to the grids of the modulator tubes. This unbalance is caused by the effect of the grid capacity to ground on the phase shifting circuit. In its broadest aspect the object of the present invention is to provide means to correct or compensate or neutralize this unbalanced effect so that equal excitation voltage is maintained on each grid.

The novel features of my invention have been pointed out with particularity in the claims attached hereto.

The nature of my invention and the mode of operation thereof will be better understood by the following detailed description thereof and therefrom when read in connection with the drawings, throughout which like reference characters indicate like parts and in which:

Figure 1 illustrates a phase modulator which includes the novel correction means of the present invention; while,

Figure 2 illustrates a modification of the arrangement of Figure 1.

Referring to Figure 1, a pair of electron discharge repeater tubes 1 and 2, which may be of the thermionic screen grid type, have their control electrodes 6 and 7 connected through leads 8 and 9 to a blocking condenser 10, which is in turn connected with any source of substantially constant high frequency oscillations, as, for example, the source D. Oscillations from the source D are impressed by way of condenser 10 on to the electrodes 6 and 7 substantially cophasally. The relative phase of these oscillations is shifted, however, since the oscillations reaching the grid 7 pass through a phase advancing means in the form of a variable condenser 11, while the high frequency oscillations reaching the grid 6 pass through a phase retarding means in the form of an inductance 12.

The anode electrodes 13 and 14 are connected together and to the terminal of a tank circuit 15 which includes an inductance 1 and a variable capacity 16. The tank circuit 15 is tuned to resonance at the frequency of the oscillations supplied from D. The high frequency oscilla-

tions, slightly shifted in phase, and impressed on to the control electrodes 6 and 7, are repeated and amplified in the tubes 1 and 2, and the energy from 1 and 2 appears in the tank circuit 15 shifted 5 in phase an amount determined by the phase shift impressed on the energy by the elements 12 and 11. Anode potential for the tank circuit 15 is supplied by way of a lead 18 connected with the positive terminal of source 20.

10 Energy for the filaments of the tubes 1 and 2 is supplied by leads 19 from the source 20.

A low impedance path for the high frequency oscillations repeated in 1 and 2 is provided by a by-passing condenser C connected, as shown, 15 between a terminal of tank circuit 15 and the filament of the tubes, thereby shunting said frequency around the source 20. Normal direct current biasing potentials for the control electrodes 6 and 7 of tubes 1 and 2 are supplied by way of resistances R₁ and R₂ from lead 22 connecting a point on the secondary winding 23 of modulation transformer T to a movable point on potentiometer P₁ connected in shunt with a portion of the battery 20, or other source. High frequency oscillations appearing in the input circuits of tubes 1 and 2 some of which passes through resistors R₁ and R₂ are provided with a low impedance path to the filament by way of by-passing condensers C₁ connecting the terminals of resistances 25 R₁ and R₂ to the filament lead 19, as shown.

30 Applicant has now described the manner in which the high frequency oscillations originating in D are applied shifted in phase, but in a sense cophasally, to the control electrodes of the tubes 35 K and L, amplified and repeated therein, and transferred therefrom substantially in phase to the tank circuit 15, from which they may be utilized.

35 The manner in which these oscillations are modulated in phase or frequency at signal frequency will now be pointed out.

40 The primary winding 24 of modulation transformer T is connected with any source of modulating potentials B in such a manner that modulating potentials are supplied in phase opposition to the control electrodes 6 and 7 of tubes 1 and 2.

45 The effect of said potentials being applied in phase opposition to the control electrodes 6 and 7, and the manner in which said signal oscillations are applied thereto in opposition, modulate in phase or frequency the high frequency oscillations repeated therein, will be set forth now.

50 Assume that no modulating frequencies are applied to the control grid electrodes of tubes 55 1 and 2. The same direct current biasing potential is supplied to the control electrodes, and the high frequency oscillations impressed on the control electrodes are substantially in phase, being shifted only by the equal but different sense 60 of impedances of the inductance 12 and capacity 11. The anode circuit of tube 1 will supply, therefore, to the tank circuit, energy equal in amount to the energy supplied to the tank circuit 15 from the anode of tube 2. The energies from 65 these tubes will be of different phase and the energy supplied from the tank circuit to the frequency doubler or next stage will have a resultant phase determined by the phase of the 70 separate energies supplied from the tubes 1 and 2, so that in this case the carrier oscillations will have no change or shift in phase.

75 In the discussion of the operation of the phase modulating arrangement of Figure 1 which follows it will be assumed that signal frequency potentials are being supplied in phase opposition

to the control electrodes 6 and 7 of tubes 1 and 2 by way of transformer T from source B.

The energy supplied to the tank circuit 15, from the tube which has the highest positive modulating potential applied to the grid electrode, will be greater in amplitude than the energy supplied to the tank circuit 15 from the tube having a lesser positive modulating potential applied to its grid. This is due to the fact that the effective potential applied to the grid of a tube governs 10 the internal impedance of the tube, the amplification thereof, and other characteristics. Each of these variables in turn effect the amount of energy supplied to the anode circuit of the tube. Therefore, varying in phase opposition the effective 15 potentials of the grid electrodes of the tubes 1 and 2, by modulating potentials from the source B, varies differentially the amount of energy said tubes will supply to the tank circuit 15. This in similar fashion varies differentially the 20 phase of the oscillations appearing in tank circuit 15.

The maximum possible phase deviation of the carrier is determined by the adjustment of impedances 11 and 12 of the grid phase shifting 25 circuits. The phase shift, therefore, of the resultant energy in the tank circuit 15, is limited by the adjustments applied to the phase shifting circuits. The frequency of the phase deviation of the carrier is determined by the modulating frequency. The amount of phase deviation of the carrier is determined by the amplitude of the modulating frequency and is proportional to the amplitude of the modulating frequency. The amount of phase shift or deviation of the 30 carrier or the tank circuit oscillations may, accordingly, be limited by the adjustments of the phase shifting circuits connected with the input of the tubes. The amounts of phase shift or deviation of the carrier or the tank circuit 40 oscillations is determined by the amount or difference of power delivered by one tube over the power delivered by the other tube, and by the phase difference of the energy delivered by both tubes. In other words, the phase shift of the 45 oscillations in the tank circuit 15 is the result of the increase of energy delivered by one tube while the energy delivered by the other tube decreases a like amount because of the phase difference in the alternating current energy delivered by each tube, and is proportional to said 50 increase and decrease.

The phase shifts which take place, as indicated above, will be multiplied or increased by a frequency multiplier in case the oscillations from 55 the tank circuit 15 are fed by way of a frequency multiplier or multipliers to the utilization circuit.

The phase or frequency modulator of the present invention, as described hereinbefore, is similar 60 in many respects to the phase or frequency modulator disclosed in application Serial No. 616,026, filed June 8, 1932. In the said application, however, the modulating potentials are applied to the screen grid electrodes of the tubes 1 and 2, 65 whereas in the present arrangement the modulating potentials are impressed, as set forth above, on the control electrodes 6 and 7. The result obtained and the operation is, in general, the same in each case.

70 In the present invention the screen grid electrodes 24 and 25 are connected, as shown, to a movable point on a potentiometer P₂ connected in shunt with the battery 20. This arrangement permits regulation of the amplification of the 75

tubes 1 and 2 since, as is well known, the potentials applied to the screen grid electrode of an electron discharge tube determine to a large extent the amplification of said tube by changing the tube impedance. Radio frequency oscillations are prevented from reaching the source 20 by way of the screen grid electrodes by connecting by-pass condensers C₁ between the screen grid electrodes 24 and 25 and the filament lead 19, as shown.

In practice, and in particular where high frequencies are to be used, the grid to filament and screen grid capacity K₂ of tube 2 has the effect of reducing or subtracting from the amount of excitation voltage reaching the grid 7, but the grid to filament and screen grid capacity K₁ of tube 1 has the effect of increasing or adding to the amount of excitation voltage reaching the grid 6. In other words, the grid to filament and screen grid capacity K₁ in tube 1 tunes out part of the inductive impedance of element 12 and thereby reduces the total impedance between the source D and grid 6. This increases the excitation to grid 6. However, the grid to filament and screen grid capacity K₂ in tube 2 by-passes part of the excitation on grid 7 to ground and thereby has a subtracting or reducing effect. This causes an unbalanced condition which produces objectionable distortion in the resultant signal modulated carrier.

This distortion may be overcome in accordance with the present invention by balancing the excitation voltage reaching the grids. There are numerous ways of accomplishing this balance but most of them have disadvantages which make their use undesirable. One such method is to make the value of resistances R₁, R₂ small as compared with the value of the impedances of K₁ and K₂. This has the disadvantage of requiring more excitation power from the source D and this method of balancing can not produce but can only approach a controlled balanced condition.

Preferably, a balanced condition is obtained in accordance with the present invention by introducing a variable resistance R_s, or if desired a fixed resistance element R_s in series with inductance 12, as shown in Figure 1. By choosing the proper value of resistance R_s, (which is preferably non-inductive) the amplitude of the excitation voltage on the grid of tube 1 may be made the same as that on the grid of tube 2. By analyzing this new phase retarding circuit 55 vectorally it will be seen that R_s reduces by a small amount the phase retarding angle, but this may be corrected by slightly increasing the inductance of L. In this manner distortion arising from unbalanced excitation may be overcome without the usual disadvantages.

In a preferred embodiment of the invention the resistance R_s of Figure 1 may be eliminated and the inductance coil L, used for retarding the phase of the energy supplied to the grid of tube 1, may be constructed of resistance wire so that the coil L, in addition to providing the phase retarding effect, serves as the voltage reducing means so that potential of the oscillations appearing on the grid of tube 1 may be exactly equal to the potential of the oscillations appearing on the grid of tube 2. This results in that a balanced effect is obtained and no distortion is introduced into the signal energy. Such an arrangement has been shown in Figure 2. The arrangement shown in Figure 2 is otherwise the

same as the arrangement shown in Figure 1. A detailed description thereof is thought unnecessary at this point.

In operation of the arrangement of Figure 2 the high frequency carrier from D is modulated 5 in frequency in accordance with the signals from B in the same manner in which modulation of the carrier by the signal is accomplished in the arrangement of Figure 1.

Moreover, the unbalancing of the modulators 10 1 and 2, due to the grid to filament and screen grid capacities K₂ and K₁ of the tubes 2 and 1 respectively, which results in distortion of the modulated signal, is overcome here or compensated by the effect of the resistance of the inductance 12 on the potential of the oscillations applied from the source D to the control electrodes 6 and 7 respectively. In this manner the potential of the high frequency oscillations appearing on the grids of each of the tubes 1 and 2 is made equal and no distortion is introduced into the signal energy.

The frequency modulated carrier free of distorted signal components may be applied to any utilization circuit. The utilization circuit may be 25 an antenna, a transmission line, or a translating device. Before utilizing the frequency translated waves they may be passed through a frequency multiplier or multipliers 30 to increase the frequency of the frequency modulated signals. The unit 30 may include an amplitude limiter which either precedes or follows the frequency multipliers. The amplitude limiter takes care of any amplitude modulation inherently produced in the frequency modulator. The signals from the unit 30 may be utilized in any known manner or may be passed to a thermionic amplifier 31 wherein the amplitude of the signal modulated carrier is increased before said modulated carrier is impressed upon the work 40 circuit, which may be an antenna F.

Having thus described my invention and the operation thereof, what I claim is:

1. Signalling means comprising, a pair of electron discharge tubes each having an anode electrode and a control electrode and having their anode electrodes connected in parallel, a source of high frequency oscillations, phase shifting means connecting said source to the control electrode of one of said tubes, phase shifting means 45 connecting said source to the control electrode of the other of said tubes, one of said phase shifting means comprising a turn or more of resistance wire, and means for applying signal oscillations in phase opposition to the impedances 50 of said tubes.

2. In a modulating device, a pair of electron discharge tubes each having an anode, a cathode and a control grid electrode, a circuit connecting the anodes of said tubes in parallel, said circuit 60 including an inductance and a capacity, a resistance connected between the control grid and cathode of each of said tubes, a circuit for applying modulating potentials in phase opposition to the control grids of said tubes by way of said resistances, and separate circuits for connecting the control grid electrode of each of said tubes to a source of carrier frequency oscillations, said circuits including phase advancing and phase retarding means respectively, the circuit including 65 phase retarding means also including amplitude regulating means, whereby the carriers on the respective grids are of equal amplitude.

3. In a signalling system, a pair of electron discharge tubes, each having a control electrode, 75

- an inductive reactance having one terminal connected to the control electrode of one tube, a capacitative reactance having one terminal connected to the control electrode of the other tube,
5 a circuit for applying oscillations of like frequency and phase to the free terminal of each of said reactances, and a device connected with the control electrode of one of said tubes for regulating the amplitude of the oscillations reaching
10 said control electrode by way of the reactance connected therewith.
4. In a phase modulating system, a pair of electron discharge tubes each having a control grid, a cathode and an anode, an output circuit
15 connected to the anode and cathode of each of said tubes, an inductive reactance having one terminal connected to the control grid of one of said tubes, a capacitive reactance having one terminal connected to the control grid of the other of said tubes, a circuit for applying carrier waves to be modulated of like frequency and phase to the free terminal of each of said reactances, circuits for applying modulating potentials in phase opposition to the like electrodes of said tubes, and a device for regulating the amplitude of the carrier to be modulated on the control grid of one of said tubes.
20
5. In a phase modulating system, a pair of electron discharge tubes each having a control grid electrode and a cathode, an inductive reactance having one terminal connected to the control grid electrode of one tube, a resistance in said connection, a capacitive reactance having one terminal connected to the control grid electrode of the other of said tubes, an impedance connected between the control grid electrode and cathode of each of said tubes, a circuit for applying oscillations of carrier frequency in phase to

the free terminal of each of said reactances, and a circuit for applying modulating potentials in phase opposition to said impedances.

6. In a signalling system, a pair of electron discharge tubes each having a control electrode and an anode and having their anode electrodes connected in parallel, a source of high frequency oscillations, a coupling device connected to said source, a circuit including inductive reactance connecting said coupling device to the control electrode of one of said tubes, a circuit including a capacitive reactance connecting said coupling device to the control electrode of the other of said tubes, amplitude regulating means comprising a resistance in one of said connections, a source 15 of signalling potentials, and circuits applying signalling potentials from said source in phase opposition to like electrodes of said tubes.

7. In a signalling system, a pair of electron discharge tubes each having a control grid, an 20 anode, and a screen grid electrode between said anode and control grid, a source of high frequency oscillations, a coupling device connected to said source of high frequency oscillations, a circuit including phase retarding means connecting said coupling device to the control electrode of one of said tubes, a circuit including phase advancing means connecting said coupling device to the control electrode of the other of said tubes, an 25 amplitude regulating resistance in one of said connections, a source of signal potentials, a circuit applying signal potentials in phase opposition from said source of signal potentials to the control electrodes of said tubes, and means for applying positive potentials to the screen grid 30 electrodes of said tubes.

GEORGE L. USSELMAN.
